tion of Illinois

Application August 16, 1948, Serial No. 44,566

6 Claims. (Cl. 30—221)

1

This invention relates to shearing handpieces and more particularly to means for providing a rigid support for a comb on such a handpiece.

It is customary for shearing handpiece manufacturers to make handpieces in a plurality of sizes and capacities so that a user may have some choice in the width of the comb and cutter of the handpiece. The reason for this is that some users require a handpiece having a relatively wide comb and cutter and other users desire a handpiece having a narrow comb and cutter. Too, in some countries the width of the comb and cutter is limited by statute. From experience it has been found that the same driving mechanism may be utilized to drive the cutter mechanism whether the comb and cutter are narrow or relatively wide. In an effort therefore to simplify manufacturing and to effect standardization of parts of handpieces both the narrow combs and the relatively wide combs have been formed with mounting slots or apertures of substantially the same size spaced apart the same distance. Thus the same mounting screws can be used to secure either type of comb to the handpiece. While this standardization of parts has been satisfactory from a manufacturing standpoint it has not been entirely satisfactory from an operator's or user's standpoint. Users have found that while a narrow comb, such as a ten-tooth comb, is generally satisfactorily secured to the handpiece with conventional mounting screws, that a relatively wide comb, such as a thirteen-tooth comb, when mounted by the conventional mounting screws is not satisfactorily secured to the handpiece. For example, as the cutter moves between its lateral positions back and forth across the comb the extreme edge portions of the comb are displaced during the shearing operation. This is believed to be due to the tension force applied to the cutter to hold the latter in engagement with the comb; that is the tensioning force is so great that it causes the edges of the comb to be deflected away from the cutter, particularly during the shearing operation, when the cutter is in either of its extreme lateral positions. As a consequence, a good shearing action is not effected on the edges of the comb of the handpiece. This of course is objectionable from the standpoint of reducing the efficiency of the user of the handpiece.

Accordingly, it is an object of this invention to provide a novel means for securing a comb to the handpiece which insures that the comb is reinforced along its lateral edges for preventing displacement thereof during a shearing operation.

Another object of the invention is to provide means for securing the comb to the handpiece so that either a narrow or a relatively wide comb

2

may be secured to the handpiece in a rigidly supported manner throughout the entire area engaged by the cutter.

Another object of the invention is to provide novel means for securing combs of different widths to the handpiece which permits the manufacturer to standardize mounting hole dimensions on the combs, which is positive in its action, which is simple in construction, and which is relatively inexpensive to manufacture.

Other objects and advantages of the invention will become apparent from the following detailed description taken in connection with the accompanying drawings, in which—

Figure 1 is a side elevational view of a shearing handpiece embodying the present invention;

Fig. 2 is a fragmentary bottom view of the handpiece shown in Figure 1;

Fig. 3 is a sectional view taken substantially along the line 3—3 of Fig. 2 and showing the parts in a partially assembled position;

Fig. 4 is a sectional line taken substantially along the line 4—4 of Fig. 2 and showing the parts in a partially assembled position;

Fig. 5 is a bottom view of a cutter with a modified form of the invention;

Fig. 6 is a sectional view taken substantially along the line 6—6 of Fig. 5;

Fig. 7 is a sectional view taken substantially along the line 7—7 of Fig. 5, showing the part in an unassembled position, and

Fig. 8 is a sectional view taken substantially along the line 8—8 of Fig. 5 showing the part in an unassembled position.

Referring now to the drawings, the invention is shown embodied in a shearing handpiece for shearing sheep and the like. In general, the handpiece includes a handle portion 11, a comb 12, a cutter 13, means 14 (of which only a portion is shown) for driving the cutter 13, and tensioning means 16 for adjusting the pressure between the cutter 13 and the comb 12. As shown, the handle portion 11 is of tubular construction shaped to be conveniently grasped by an operator. The comb 12 projects outwardly from the forward end of the handle portion 11 as by having its base 17 secured on a shoulder 18, formed on the underside of the forward end of the handle portion 11, as by mounting screws 19. The cutter 13 is mounted on top of the comb 12 and is arranged to be driven back and forth across the comb by the driving means 14. Of the latter, only a yoke 21 drivingly interconnected with the cutter 13 and a pivotally mounted fork 22 are shown. The yoke 21 is formed with downwardly extending projections 23 shaped to be received in spaced recesses (not shown) formed on the upper surface of the cutter 13. At its rear end a shank 24 of the yoke 21 is received in a sleeve 25 forming a part of the fork 22. The tension-

ing means 16 includes a tension pin 26 having one end seated in a bearing socket formed in a boss 27, integral with the fork 22, and having its other end, not shown, extending through a sleeve projection 28. The latter is integral with the forward end of the handle portion 11 and is inclined rearwardly of the front end of the handle portion. The extreme end (not shown) of the tension pin 26 abuts against a cap 29 threadable on the sleeve projection 28. The pressure between the cutter 13 and the comb 12 may be adjusted by varying the position of the cap 29 relative to the sleeve 28.

One phase of the invention is concerned with means for mounting the comb 12 on the handle portion 11 so that the comb is prevented from being displaced relative to the handle portion 11 during a shearing operation. For this purpose, in the embodiment of the invention shown in Figs. 1-4 a plate 31 is disposed between the heads of the mounting screws 19 and the base 17 of the comb 12. As shown in Figs. 3 and 4 in which the parts are in a partially assembled position, that is the screws 19 are not tightened up, the plate 31 has a concavo-convex cross section in both a transverse and a longitudinal direction. The plate is of substantially the same thickness as the comb 12; has substantially the same overall width as the base 17 of the comb; and extends along the longitudinal axis of the handpiece from the rearward edge of the base 17 to a point adjacent the base of the teeth 32 of the comb 12. The plate is preferably formed of resilient material. With this construction the plate 31 in the partially assembled position, initially engages the comb base 17 at four positions defined by the corners 30 and 30' respectively of the plate. The forward corners 30 of the plate 31 engage the comb adjacent the base of the comb teeth 32 and adjacent the lateral edges of the base 17. The rearward corners 30' of the plate 31 engage the base 17 of the comb 12 adjacent the rear edge of the base and adjacent the lateral edges thereof. When the screws 19 are tightened the central portion of the plate 31 is drawn against the comb. As a consequence the marginal portions of the plate and particularly the corner portions thereof are stressed to exert a pressure of greater degree against the comb. This distribution of pressure serves to prevent the comb from being displaced away from the plane of the cutter teeth during operation of the handpiece. The pressure of the clamping plate has an equalizing effect throughout the width of the comb so as to equalize as well as minimize any tendency toward deflection incident to cutter pressure. There is, of course, a small degree of deflection in the comb teeth due to their small cross-section, but this is substantially uniform with the present invention. Thus the plate 31 when in its assembled position provides a pressure equalizing support as well as a reinforcement for the comb. The forward edge of the plate 31 may be beveled as shown at 33 to permit the handpiece to be guided readily over the skin of the animal. The mounting holes in the plate 31 for the screws 19 are preferably counterbored so that when the screws 19 are in a tightened or securing position the heads thereof do not interfere with the free movement of the handpiece over the skin of an animal.

In the embodiment shown in Figs. 5-8 two generally Y-shaped or forked members 35 and 36 formed from resilient material are utilized as a means to clamp a comb 37 to a handpiece 34 to

prevent relative displacement of the comb with respect to the handpiece during the shearing operation.

The Y-shaped member 35 includes a stem 38 and arm portions 39 and 41. The stem 38 as seen in Fig. 8 is formed with an aperture 42 having a rounded bottom for receiving the correspondingly shaped head of a mounting screw 43. At the extreme end of the stem 38 is a projection 44 shaped to engage the lateral portion of the underside of the base 46 of the comb 37. On its arm portions 39 and 41 the Y-shaped member is formed with projections 48 and 49, respectively, shaped to engage spaced positions disposed centrally of the base 46 of the comb 37. The Y-shaped member 36 is of similar construction having a stem portion 51 with a central aperture 52 for receiving a mounting screw 43 and arm portions 53 and 54. The stem and arm portions are provided with projections 56, 57 and 58 respectively, shaped to engage the underside of the base 46 of the comb 37 in a manner similar to that described for the Y-shaped member 35. As shown in Fig. 5 the arms of the Y-shaped member 36 overlap the arms of the Y-shaped member 35. For this purpose the Y-shaped member 35 is formed with a recessed portion 59 on its top side which interfits with a similar recessed portion 61 on the underside of the Y-shaped member 36. As shown in Fig. 6, when the screws 43 are in their securing position, the portion of the stems 38 and 51 adjacent the respective mounting holes is forced into engagement with the bottom of the comb. Because the portions of the Y-shaped members 35 are bowed when the screws 43 are tightened it is to be understood that stresses are set up in the members 35 and 36 to constantly urge the projections into engagement with the comb. Thus, forces for holding the comb 37 in position are applied at lateral positions on the base of the comb and at spaced positions at the central portion of the base of the comb. Thus, this construction provides a comb securing means in which the comb is positively reinforced by the application of equalized pressure at spaced points substantially along the full width of the comb.

It will be observed that in both embodiments pressure is applied along substantially the full width of the comb by means of one or a multiple of clamping plates. This distributes the pressure at pre-determined areas on the clamping plate spaced laterally from the clamping screws 19. This distribution of the pressure has an equalizing effect which serves to provide what might be termed a stabilized support for the clamping plate. This pressure distribution serves to effectively prevent uneven deflection of the comb and particularly deflection of the end portions of the cutter from the true plane in which its cutting edges are designed to operate. These pressure equalizing and stabilizing effects function to promote a finer degree of precision in coaction between the cutting edges of the comb and the cutter from end to end of the comb, with the result that the shearing action is improved. Also, the tendency toward dulling of the cutting edges due to comb deflections is reduced, with consequent improvement in the life of the comb and cutter.

The embodiments of the invention shown herein are exceedingly simple in construction. Either construction permits of standardization of parts. Thus, either a narrow ten-tooth comb or a relatively wide thirteen-tooth comb provided with standard spacing between the mounting holes may be secured to the handle portion having con-

ventionally spaced mounting screws. As a result of the constructions disclosed herein a relatively wide comb may be secured to the handpiece 11 in a rigid manner without requiring a specially designed handpiece.

While I have shown two embodiments of my invention it will be understood that I do not wish to be limited thereto since many other modifications may be made and I therefore contemplate by the claims to cover such modifications as fall within the true spirit and scope of my invention.

I claim:

1. In a shearing handpiece, the combination of a handle portion, a comb projecting outwardly from the handle portion and having a base portion seated thereon, a cutter movable back and forth across said comb between extreme lateral positions, tensioning means engageable with said cutter for applying a pressure thereto to urge the cutter into engagement with the comb, resilient plate means disposed adjacent the comb and shaped when initially assembled adjacent the comb to engage the latter at a plurality of spaced positions, two of said positions being adjacent opposite lateral edges of said comb, and means for securing the plate means to the comb and deforming said plate means to a position in which the portions thereof adjacent the securing means are in contiguous relation with the comb, and said plate means is stressed to urge the lateral portions thereof into engagement with the lateral edges of the comb to provide a support for the comb to positively retain the lateral edge portions in a fixed position as the cutter moves between its lateral positions.

2. In a shearing handpiece, the combination of a handle, a comb projecting axially outwardly from the handle and having a base portion seated on said handle, a blade movable back and forth across said comb between lateral positions, tensioning means engageable with the blade for applying a pressure thereto to force the blade into engagement with the comb, a plate movable between a position in which it has a surface which is generally concave in both a transverse and a longitudinal direction, and a position in which said surface is in contiguous relation with the comb, said plate in the latter position being stressed to have its edge portions urged into engagement with the comb, abutting against said base portion to provide a reinforced support for the comb as the cutter moves between its lateral positions, and means for securing the plate in its last mentioned position.

3. In a shearing handpiece, the combination of a handle, a comb projecting outwardly from the handle and having a base portion seated on said handle, a blade movable back and forth across said comb between extreme lateral positions, tensioning means engageable with the blade for applying a pressure thereto to urge the blade into engagement with the comb throughout its path of travel, a first forked member having projections on each of its arm portions engageable with the base portion at spaced axial positions disposed centrally thereof and having a projection on its stem portion engageable with the base portion along one lateral edge thereof, a second forked member having projections on each of its arm portions engageable with the base portion at spaced axial positions disposed centrally thereof and having a projection on its stem portion

engageable with the base portion on its other lateral edge, and means for securing the forked members and the comb to the handle so that the forked members are under stress and the projections are constantly urged into engagement with the comb to provide a reinforcement for the comb for preventing displacement thereof at either lateral edge or an intermediate position during the movement of the cutter between its extreme positions.

4. The combination recited in claim 3 in which the arm portions of the first forked member overlap the arm portions of the second forked member.

5. In a shearing hand piece, the combination of a handle, a comb projecting axially outwardly from the handle and having a base portion seated on said handle, a blade movable back and forth across said comb between extreme lateral positions, tensioning means engageable with the blade for applying a pressure thereto to urge the blade into engagement with the comb throughout its path of travel, a first forked member having its arm portions shaped to engage spaced central positions of the base portion and its stem portion shaped to engage one lateral edge of the base portion, a second forked member having its arm portions shaped to engage spaced central positions of the base portion and having its stem portion shaped to engage the opposite lateral edge of the base portion, and means extending through each of said forked members for securing the forked members and the comb to the handle, said forked members in their assembled positions providing a reinforcement for the comb for preventing displacement thereof at either lateral edge or an intermediate position during the movement of the cutter between its extreme positions.

6. In a shearing handpiece having a head equipped with a comb and a cutter, the comb having a flat body portion and teeth extending forwardly therefrom, means for oscillating the cutter, and tensioning means for applying pressure against the cutter to maintain it in coaction with the comb, the combination of a plate structure adapted to be applied to the under side of the comb body portion, the plate structure having contact portions arranged to engage the under side of the comb body portion at points transversely spaced thereon and adjacent to the outer opposite edges thereof and having additional contact portions for engaging the under side of the comb body portion at points longitudinally spaced thereon, the plate structure intermediate said contact portions being spaced from the under side of the comb body portion when the plate structure is positioned on the comb body portion, and clamping means for applying pressure to said intermediate portion of the plate structure to thereby apply pressure through said contact portions against the comb body portion at said transversely and longitudinally spaced points.
